UNITED STATES PATENT OFFICE.

ALLEN PARKER WILSON, OF WALTHAM, MASSACHUSETTS, ASSIGNOR TO BOSTON PENCIL POINTER COMPANY, OF WALTHAM, MASSACHUSETTS, A CORPORATION OF MASSACHUSETTS.

METHOD OF MAKING CUTTERS FOR PENCIL-SHARPENERS.

1,383,046.

Specification of Letters Patent. Patented June 28, 1921.

Application filed April 21, 1919. Serial No. 291,522.

To all whom it may concern:

Be it known that I, ALLEN P. WILSON, a citizen of the United States, and resident of Waltham, in the county of Middlesex and 5 State of Massachusetts, have invented a new and useful Improvement in Methods of Making Cutters for Pencil-Sharpener, of which the following is a specification.

This invention relates to improvements in 10 the method of making cutters for pencil sharpeners with the object in view of providing a hollow cutter which is developed from sheet metal.

Another object is to provide a cutter of 15 this character in which a sheet metal blank of rectangular form is distorted to produce one or more pencil sharpening ribs and the blank then being curved and its side edges united to form a tube having the sharpening 20 rib or ribs arranged straight and exteriorly thereon.

A practical embodiment of my invention is represented in the accompanying drawings in which,

25 Figure 1 represents a plan view of a piece of sheet metal from which a blank for my improved cutter is taken.

Fig. 2 represents an edge view of the same.

Fig. 3 represents a plan view of the blank 30 distorted to produce the pencil sharpening ribs thereon.

Fig. 4 represents a section taken in the plane of the line IV—IV of Fig. 3.

Fig. 5 represents a side view of the cutter 35 as it appears when curved into cylindrical form, the straight exterior pencil sharpening ribs being arranged longitudinally thereon.

Fig. 6 represents an end view of the same.

40 Fig. 7 represents a central section of the same.

Fig. 8 represents a horizontal section taken in the plane of the line VIII—VIII of Fig. 5 looking in the direction of the 45 arrows.

The cutter comprises a tube 1 shown cylindrical in the present instance and it is produced as follows:

A blank 2 of rectangular form is cut from 50 a piece of sheet metal 3 and is distorted by stamping, rolling, or otherwise to produce thereon pencil sharpening ribs 4 which project outwardly from the surface of the blank. These sharpening ribs are formed

parallel to the side edges 6 so that when the 55 blank is curved into its tubular form, the straight exterior sharpening ribs will be arranged longitudinally thereon with the abutting side edges 6 meeting at a point between two sharpening ribs as clearly shown in 60 Fig. 5. The side edges 6 may be permanently united by any well known or approved means.

The curving of the blank into tubular 65 form may be accomplished by any suitable device of well known or approved type.

It is to be understood that after the above operations are completed the tube may be hardened by any well known or approved 70 process, and if so desired the straight sharpening ribs may be suitably sharpened.

What I claim is:

1. The method of producing sheet metal cutters for pencil sharpeners comprising distorting a sheet metal blank to produce one 75 or more pencil sharpening ribs, curving the blank into a tube having the rib or ribs arranged straight and exteriorly thereon, and uniting the meeting edges of the blank.

2. The method of producing sheet metal 80 cutters for pencil sharpeners comprising distorting a sheet metal blank to produce one or more pencil sharpening ribs, curving the blank into a tube having the rib or ribs arranged straight and exteriorly thereon, uniting 85 the meeting edges of the blank and sharpening said ribs.

3. The method of producing sheet metal cutters for pencil sharpeners comprising distorting a sheet metal blank of rectangular 90 form to produce one or more pencil sharpening ribs, curving the blank into a tube having the rib or ribs arranged straight and exteriorly thereon, and uniting the meeting edges of the blank and sharpening said ribs. 95

4. The method of producing sheet metal cutters for pencil sharpeners comprising distorting a sheet metal blank of rectangular form to produce one or more pencil sharpening ribs, curving the blank into a tube having 100 the rib or ribs arranged straight and exteriorly thereon, uniting the meeting edges of the blank and sharpening said ribs.

In testimony, that I claim the foregoing as my invention, I have signed my name this 105 14th day of February 1919.

ALLEN PARKER WILSON.
